CLAIM

The ornamental design for a cooking device for holding food-containing bags, as shown.

DESCRIPTION

FIG. 1 is a side elevational view of a cooking device for holding food containing bags showing our new design;

FIG. 2 is a left end elevational view thereof;

FIG. 3 is a right end elevational view thereof;

FIG. 4 is a top plan view thereof;

FIG. 5 is a bottom plan view thereof;

FIG. 6 is a perspective view thereof.
